UNITED STATES PATENT OFFICE.

ALVIN K. LEE, OF CHAPARAL, ARIZONA TERRITORY.

CARRIER.

No. 904,337.

Specification of Letters Patent.

Patented Nov. 17, 1908.

Application filed January 2, 1908. Serial No. 408,982.

To all whom it may concern:

Be it known that I, ALVIN K. LEE, a citizen of the United States, and a resident of Chaparal, in the county of Yavapai and Territory of Arizona, have invented a new and Improved Carrier, of which the following is a full, clear, and exact description.

The invention relates to bundle carriers, and its object is to provide a new and improved carrier, more especially designed for use on cans, pails and like receptacles, and arranged to permit placing the carrier conveniently in position on the receptacle or removing it therefrom, and to allow of folding the carrier into a comparatively small space for shipping, storing or other purposes.

The invention consists of novel features and parts and combinations of the same, which will be more fully described hereinbelow and then pointed out in the claims.

A practical embodiment of the invention is represented in the accompanying drawings forming a part of this specification, in which similar characters of reference indicate corresponding parts in all the views.

Figure 1 is a side elevation of the improvement as applied; Fig. 2 is a perspective view of the improvement; Fig. 3 is an enlarged transverse section of one of the joints, the section being on the line 3—3 of Fig. 2; and Fig. 4 is a plan view of the supporting collar.

The collar A of the carrier is preferably made from a single piece of wire formed at diametrically opposite points into aligned coils A', A², provided in their openings with bearings B, B', preferably in the form of eyelets, having their ends provided with outwardly-extending flanges (see Fig. 3), to hold the bearings in position in the coils A', A². The bearings B, B' are engaged by inwardly-extending trunnions C', C², formed on the ends of a bail C. Now in using the device, the collar A is slipped in position on the body of the can, pail or other receptacle D, as plainly indicated in Fig. 1, and then the bail C may be swung up into a vertical position and taken hold of by the user, to

carry the receptacle about from one place to another. By reference to Fig. 4 it will be seen that the collar A is practically rendered completely circular at its inner face, to snugly fit the body of the receptacle D, either at the enlarged upper end thereof, or under an annular shoulder formed on the receptacle, as is the case with cans for containing paint and the like. The coils A', A² extend outwardly from the collar A, and the trunnions C' and C² of the bail C may be readily inserted in the coils whenever it is desired to use the device for carrying the receptacle about.

The collar shown and described is very simple and durable in construction, and can be folded into a comparatively small space for shipping, storing and other purposes by turning the bail into the plane of the collar, and the carrier can be readily applied on a receptacle or removed therefrom whenever it is desired to do so.

The ends of the wire from which the collar A is formed, are formed into the coil A², as clearly shown in Fig. 4.

Having thus described my invention, I claim as new and desire to secure by Letters Patent:

1. A carrier comprising a collar made of a piece of wire formed at diametrically opposite points into coils, bearings fitting into the openings of the said coils, and a bail having trunnions engaging the said bearings.

2. A carrier comprising a collar made of a piece of wire formed at diametrically opposite points into coils, bearings fitting into the openings of the said coils and having their ends provided with flanges engaging the ends of the coils to hold the bearings in position in the coils, and a bail having trunnions engaging the said bearings.

In testimony whereof I have signed my name to this specification in the presence of two subscribing witnesses.

ALVIN K. LEE.
